[57] CLAIM

The ornamental design for a combined air foil and retractable awning, as shown.

DESCRIPTION

FIG. 1 is a front perspective view of a combined air foil and retractable awning showing my new design; FIG. 2 is a rear perspective view thereof on a greatly reduced scale, it being understood that the broken lines are for illustrative purposes only;

FIG. 3 is an end elevational view thereof; FIG. 4 is a top plan view thereof;

FIG. 5 is a front elevational view thereof; FIG. 6 is a bottom plan view thereof;

FIG. 7 is a rear elevational view thereof;

FIG. 8 is a sectional view thereof taken along line 8—8 in FIG. 4; and FIG. 9 is a rear perspective view of FIG. 2 with the awning and one of the collapsible support rods shown in extended position.
